US00D494579S1

(12) **United States Design Patent** (10) Patent No.: **US D494,579 S**
Chuang et al. (45) Date of Patent: **** Aug. 17, 2004**

(54) **MULTIMEDIA CENTER PERSONAL COMPUTER**

D440,212 S * 4/2001 Clapper D14/125
D457,158 S * 5/2002 Awamori et al. D14/356

(75) Inventors: **Meng-Ju Chuang**, Taipei (TW);
Ping-Hung Chen, Taipei (TW);
Jeng-Cheng Lai, Taipei (TW)

* cited by examiner

(73) Assignee: **Tatung, Co., Ltd.**, Taipei (TW)

Primary Examiner—Freda S. Nunn

(**) Term: **14 Years**

(74) Attorney, Agent, or Firm—Bacon & Thomas PLLC

(21) Appl. No.: **29/195,168**

(57) **CLAIM**

(22) Filed: **Dec. 9, 2003**

The ornamental design for the multimedia center personal computer, as shown and described.

(51) LOC (7) Cl. **14-02**

DESCRIPTION

(52) U.S. Cl. **D14/314**

FIG. 1 is a front view thereof;

(58) Field of Search **D14/125, 349,**

FIG. 2 is a rear view thereof;

D14/351-356; D13/162, 184, 199; 312/223.1,

FIG. 3 is a left side view thereof;

223.3; 360/99.01-99.12; 361/680-686,

FIG. 4 is a right side view thereof;

690-696; 369/34.01, 36.01

FIG. 5 is a top view thereof;

(56) **References Cited**

FIG. 6 is a bottom view thereof; and,

U.S. PATENT DOCUMENTS

FIG. 7 is a perspective view of a first embodiment of a multimedia center personal computer showing our new design.
